[57] CLAIM

The ornamental design for a flag, as shown and described.

DESCRIPTION

FIG. 1 is a left side elevational view of a flag, showing my new design, the right side being a mirror image thereof;

FIG. 2 is a front elevational view thereof, the rear being identical;

FIG. 3 is a bottom plan view thereof, the top being identical.

The flag is of conventional thickness, and the drawing is shaded to indicate contrasting color.
